ATTY.

UNITED STATES PATENT OFFICE.

JAMES STUART WEARN, OF CHRISTCHURCH, NEW ZEALAND.

CREAM-COOLER.

1,230,960.

Specification of Letters Patent. Patented June 26, 1917.

Application filed October 5, 1915. Serial No. 54,125.

To all whom it may concern:

Be it known that I, JAMES STUART WEARN, a subject of the King of Great Britain, residing at 541 Colombo street, 5 Christchurch, in the Dominion of New Zealand, have invented new and useful Improvements in Cream-Coolers, of which the following is a specification.

This invention relates to a device for use 10 in cooling cream as it is delivered from a cream separator, its object being to provide a construction which will perform the cooling more rapidly and thoroughly than would be possible with devices at present 15 employed for this purpose. In order that the nature of the invention and its construction may be fully understood, reference will now be made to the accompanying sheet of drawings in which:—

20 Figure 1 shows the device in place upon a cream separator in readiness for use, and, Fig. 2 is a vertical section of a portion of the device, upon a somewhat larger scale, illustrating the details of its construction. 25 The said construction consists of a length of metal tubing wound so as to form a spiral or helix 1 through which a continuous flow of cold water is maintained when the device is in use. The said flow of water is 30 admitted to the lowermost point of the helix and permitted to escape from the top.

Arranged within the hollow center or core of the helix 1 at the upper end of the latter and secured in place by any suitable means, 35 as by a pin 1^a projecting from the cap and fitting between the coils of the helix as here shown, is a cap 2 having a flat upper end 3 surrounded by a flange or bead 4 the lower edge of which extends downwardly in line 40 vertically with the center of the tube constituting the upper convolution of the helix 1. The periphery 5 of the cap which fits within the core of the helix, is preferably fluted or provided with ridges, buttons or otherwise 45 formed so as to provide intervals or channels between such periphery and the internal surface of the helix. To provide a means of supporting the device in the required position, the upper end 3 of the cap 50 is furnished with a hook or ring 6 by means of which such device may be suspended from the cream spout 7 of the separator 8.

In operation, the cream, as it issues from

the spout 7, is received upon the upper side 3 of the cap 2 and overflowing the bead 4, 55 trickles down the sides of the latter. Owing to the fact that the sides of the bead are in line vertically with the middle of the tubing of the helix, as already explained, the cream will be so directed onto the top of the helix 60 that it will flow evenly down both inner and outer surfaces, the channels between the periphery of the cap and the inner surface of the helix permitting a free flow down the internal portion of the cooler. The cream 65 as it passes downward therefore forms a thin film completely enveloping the inner and outer faces of the helix and consequently presents a maximum surface to the cooling action of the water circulating through the 70 helix.

I claim:

1. A cooler of the class described comprising a vertically disposed helical coil of tubing, and a cap for the coil having a cylindrical portion fitting within the upper end of the latter, the said cylindrical portion being formed so as to provide longitudinal exterior channels for the passage of liquid between the said cap portion and the 80 surrounding convolutions of the coil, the upper end of the cap being closed and adapted to receive a flow of liquid, and an annular flange surrounding the upper end of the cap and having its edge projecting 85 downwardly therefrom, the said edge of the flange being equal in diameter to the mean of the internal and external diameters of the coil so as to direct the liquid which overflows the upper end of the cap down both 90 the inner and outer surfaces of the coil.

2. A cooler of the class described comprising a vertically disposed helical coil of tubing, and a cap for the coil having a cylindrical portion fitting within the upper 95 end of the latter, the said cylindrical portion being formed so as to provide longitudinal exterior channels for the passage of liquid between the said cap portion and the surrounding convolutions of the coil, the upper end of the cap being closed and adapted to receive a flow of liquid, and an annular flange surrounding the upper end of the cap and having its edge projecting 100 downwardly therefrom, the said edge of the flange being equal in diameter to the 105

mean of the internal and external diameters of the coil so as to direct the liquid which overflows the upper end of the cap down both the inner and outer surfaces of the coil, the said flange being formed so as to provide a raised margin for the upper end of the cap.

In testimony whereof I have signed my name to this specification in the presence of two subscribing witnesses.

JAMES STUART WEARN.

Witnesses:

PERCY RICHMOND CLIMIE,
SIDNEY JAMES TRELEAVEN.
